UNITED STATES PATENT OFFICE.

WILLIAM F. IREGANG, OF CHICOPEE, MASSACHUSETTS, ASSIGNOR TO THE FISK RUBBER COMPANY, OF CHICOPEE FALLS, MASSACHUSETTS, A CORPORATION OF MASSACHUSETTS.

FOLDER FOR PRESSURE BAGS.

Application filed July 22, 1926. Serial No. 124,195.

This invention relates to devices for folding pressure bags for insertion in pneumatic tire casings prior to vulcanization. It has for one object to avoid undue strain 5 on the inner periphery of the bag during the folding operation. It has for a further object to decrease the total overall width of the folded bag so that the insertion of the bag into a tire casing is made easier.

10 Referring to the drawings, Fig. 1 is a front elevation of an apparatus constructed in accordance with my invention;

15 Fig. 2 is a side elevation thereof;

Fig. 3 is a side elevation corresponding to Fig. 2, but showing a bag folded and released;

20 Fig. 4 is a front elevation similar to Fig. 1, but showing the bag partially folded; and

Fig. 5 is a view similar to Fig. 4, but showing the bag completely folded.

The apparatus is supported on a pedestal 10, which for a major portion of its height 25 is furnished with ways 11 in which slide a cross-head 12 and a sliding arm 13. The cross-head 12 is reciprocated vertically by means of a piston rod 14 attached at its bottom end to a piston 15 running in a pneumatic cylinder 16. A pipe 17 is attached to the top and a pipe 18 to the bottom of this cylinder, air being admitted to either one or the other of these pipes through a valve 19 from an air-line 20.

35 The sliding arm 13 is held by a threaded rod 21 having a collar 22 and handwheel 23 fixed to it. The rod is threaded into the upper side of the sliding arm and slides freely through a lug 24 attached to the top of the pedestal 10. Attached to the bottom of the sliding arm 13 is a stud 25 secured in place by a nut 26.

40 The cross-head 12 carries rollers 27 which guide it in the ways 11, and also carries a rod 28 upon which is mounted a curved plate 29. Slidéable transversely in the cross-head 12 is a rod 30 carrying at its front end a plate 31 upon which are mounted pins 32. These pins operate upon the airbag in a manner which will be described below.

45 Attached by pins 33 to the cross-head 12 are a pair of links 34 at each side of the center line of the pedestal. This construction is best shown in Figs. 1 and 2. The

links 34 are pivoted at 35 to a second pair of links 36 having bearings at 37 in bracket 38 attached to the pedestal. Extending between each pair of the links 36 at a point slightly above the pivot 35 are rods 39, carrying at their front end rolls 40 having a central grooved portion 41. Each of the links 36 carries a portion 42 acting as a stop abutting against the side of the pedestal as shown in Fig. 1 and in Fig. 5 to prevent motion of the links beyond the point desired.

55 The rod 30 is reciprocated transversely of the cross-head 12 by mechanisms which will now be described. Upon the top of the cross-head 12 is an arm 43 to which is pivoted a depending link 44 having a slot 45 at its lower end. Running in this slot is a pin 46 secured to the rear end of rod 30. The link 44 carries a second pin 47 which in the upward stroke of the cross-head 12 coacts with the lower surface of a pair of angle irons 48. 65 These angle irons are pivoted at 49 to a pair of rails 50. At their upper portion they are held in place by rods 51. A spring 52 encircles each of these rods between the angle irons and the rail 50, the rods being held in 70 position by nuts 54. As the cross-head ascends the pin 47 rides under the upper end of the angle irons 48, the angle irons yielding slightly during this motion and finally dropping below the pin 47. As the cross-head descends the pin 47 will run down the angle iron as shown in Fig. 3, finally running off the bottom end of the angle iron 75 at a point indicated by the lead line 60 (Fig. 2). During further downward movement of the cross-head, the pin 47 bears against the rail 50, so that the rod 30 is positively forced to the left as viewed in Fig. 2. This action permits the pins 32 to be projected for engagement with an airbag during the upward 80 stroke of the cross-head and to withdraw from contact with the airbag during the downward stroke.

85 In addition to the parts of the machine already described, mention may be made of two or three parts which serve to guide or position the airbag or tire being worked upon. Fastened to the curved plate 29 is a depending guard 55 which serves to prevent the airbag being drawn to the right 90 in Fig. 2 when the pins 32 are being withdrawn from contact with it by the mechanism just described. Upon rods 39 are se- 95

cured fingers 56 preferably secured in place by collars 57 having set screws 58. These fingers serve to position a tire which is placed around the airbag. Projecting from the sliding arm 13 is a bracekt carrying a saddle 59 upon which the airbag hangs during the operation.

Figs. 1, 2, and 3 show in dotted line the position of a pressure bag as it is placed on the machine for being folded. In this position the cross-head 12 is at its lowermost position and the sliding arm 13 hangs likewise in its lowermost position with the collar 22 preventing further downward movement. Assuming the bag to have been placed upon the machine and to be hanging from the saddle 59, the air valve 19 is turned so as to admit air under pressure to enter through pipe 18 into the bottom of the pneumatic cylinder 16. This causes the cross-head 12 to be raised and brings the parts into the position of Fig. 4, which represents merely a stage of transition. The parts do not stop in the position of Fig. 4, but continue to that of Fig. 5, which represents the completely folded bag. Between the position of Fig. 4 and that of Fig. 5 the rod 28 contacts with the bottom of the stud 25 raising the arm 13 from the position of Fig. 4 to that of Fig. 5. The purpose of this movement will be pointed out below. With the bag folded as shown in Fig. 5 the tire casing which usually has been expanded from flat form into tire form is placed around it, the valve 19 again operated to cause the cross-head 12 to descend and the bag to be thus straightened out inside the tire casing.

Bag folding devices of the general type described herein have been proposed previously, and my invention deals primarily with three features of the device described. The first of these is the use of the spaced pair of pins 32 as will be seen in Fig. 5. The use of spaced pins produces a gradual bend in the inner periphery of the pressure bag. In prior devices the bending of the bag at this point was caused by a single pin or by a relatively narrow plate. I have found that by the use of spaced pins as described only a slight stretching of the inner periphery of the bag will result, which is desirable on account of the tendency of the bag to break at this point if over-stretched. The second feature is the position of the rollers 40 at a point spaced from the pivot 35. It will be noted that the rod 39 supports the rolls 40 mounted upon the links 36 at a point above pivot 35, which construction is of use in securing the smallest possible overall circumference of the folded bag without causing undue buckling at any

point. The location of the rollers at this point serves to prevent the side of the bag extending too far laterally as viewed in Fig. 5.

The third feature is the vertical movement provided for in the arm 13. The vertical movement of this arm draws the bag upwardly as viewed in Fig. 5 and causes a narrowing of the overall width of the folded bag. If this feature were not used the bag would look somewhat more squatly than in this figure, and would extend sideways a considerably further distance.

Having described my invention, I claim:

1. In a machine for folding pressure bags for insertion in a tire casing a pair of spaced pins adapted to engage the outer periphery of the bag, a pair of folding devices adapted to engage the inner periphery of the bag at points spaced from the pins, and means for moving the folding devices and the pins relatively to each other, whereby the folding devices are caused to move outwardly around the pins to fold the bag around the same.

2. In a machine for folding pressure bags for insertion in a tire casing, means for producing a re-entrant bend in the bag, and means for stretching the opposite side of the bag away from the bend to cause a narrowing of the overall width of the folded bag.

3. In a machine for folding pressure bags for insertion in a tire casing a vertically movable cross-head, a vertically movable member having a limited movement, means for raising the cross-head, means of causing the member to partake of a limited movement together with the cross-head, devices carried by the cross-head for engaging the outer periphery of the bag, means for folding the bag around such devices, and means carried by said member for engaging the inner periphery of the bag at a point opposite to the devices, all constructed and arranged to cause a re-entrant bend to be made in the bag and to cause the side of the bag opposite the bend to be stretched away from the bend.

4. In a machine for folding pressure bags for insertion in a tire casing, a slideway, a device movable in the slideway for engaging the outer periphery of the bag, opposed pairs of links pivoted together and having the other end of one of the links pivoted to the said device and the other end of the other link to the slideway, and rollers for engaging the inner periphery of the bag, said rollers being located upon those links which are pivoted to the slideway at points spaced from the pivots joining the two links.

WILLIAM F. IRRGANG.
